UNITED STATES PATENT OFFICE.

ANGELO PERRI, OF GROVELAND, MASSACHUSETTS, ASSIGNOR TO REECE SHOE MACHINERY COMPANY, OF BOSTON, MASSACHUSETTS, A CORPORATION OF MAINE.

WIPING MECHANISM.

1,260,033.

Specification of Letters Patent.

Patented Mar. 19, 1918.

Application filed September 11, 1916. Serial No. 118,415.

To all whom it may concern:

Be it known that I, ANGELO PERRI, a citizen of the United States, residing at Groveland, in the county of Essex and State of Massachusetts, have invented certain new and useful Improvements in Wiping Mechanism, of which the following is a specification, reference being had therein to the accompanying drawing.

10 This invention relates to "lasting machines," and more particularly to a novel "wiping mechanism" for use in the lasting step in the manufacture of shoes.

In the lasting of shoes a sectional wooden "last" is usually employed for giving form to the shoe. The shoe upper is required to be assembled with the sole about the last, as a form, and the lasting process may comprise the steps of first "pulling-over" the flexible upper about the fore part of the shoe, and thereafter "wiping" the extending side margins and the margins at the heel and toe. Such wiping consists in forcing, smoothing and pressing the overhanging material of the upper into place about the last and inner sole, where it may be suitably secured preparatory to subsequent operations, including attachment of outer sole. In my prior Patent No. 1,168,963, granted January 18, 1916, I have shown a machine in which all of the above described steps or operations may be performed, the machine comprising a shiftable "jack" which holds the shoe, a pulling-over mechanism, and heel and toe wiping mechanisms.

The present invention pertains more especially to a wiping mechanism adapted to use at the toe end of the shoe, although various features hereof might be effectively otherwise employed; and the principal object of the present improvement is to afford a wiping mechanism which will be simple and durable in construction, and efficient and convenient in operation.

45 The present application, therefore, discloses one form or illustration of a toe wiping mechanism embodying the present invention. It may be variously employed. For example, the mechanism hereof may be employed in a so-called "bed lasting machine" in which the inverted shoe is inserted after having been pulled-over and in which usually both the heel and toe portions of the shoe upper are wiped and secured. On the 50 other hand, the mechanism hereof may be

substituted in such a machine as that of said Patent No. 1,168,963 for the toe wiping mechanism there shown. Or the mechanism hereof might, in some cases, if desirable, be employed by itself solely for the wiping of 60 toes of shoes.

The toe wiping mechanism herein illustrated is adapted to be employed in such a combination of pulling-over mechanism, jack and wiping mechanism as is shown in 65 my copending application Serial No. 132,806, filed November 22, 1916; and the features of combination and the other mechanisms are not shown or claimed herein, but are made the subject of claim in said copending 70 application.

Among the particular objects to which the present invention is directed is to provide a toe wiping mechanism adapted to efficient and convenient use for the wiping 75 of both shoes, that is, the right and left shoes of a pair. A mechanism which is quickly reversible for this purpose is very advantageous as permitting the operator to complete his work in both shoes of a pair 80 before operating upon other shoes. It is very desirable that a wiping mechanism shall be free from the necessity of separate adjusting operations to adapt it for the right and left shoes of a pair. Ordinarily separate 85 wiping plates or blades have been used for the two shoes of a pair, and it is an aim hereof to provide that a single set of wiping plates serves both for the right and 90 left shoe.

It is a plan and object hereof to so arrange that each of a single set of wiper plates may be reversed for converting it from one side to the other side of the shoe toe contour. To do this I provide that each 95 plate shall be constructed at different parts of its periphery to adapt it respectively to the contour of both sides of the shoe. By this means the reversal of both plates without shifting either of them across the longitudinal axis of the machine converts the wiping mechanism from one adapted to a right shoe to one adapted to a left shoe, and vice versa.

By this improvement, when the wiper 105 plates have been once adjusted for one shoe, no further adjustment for the other shoe is required. These desirable points constitute objects of the present invention, and further objects and advantages will be 110

elucidated in the hereinafter following description, or will be apparent to those skilled in the art.

To the attainment of the above referred 5 to objects and advantages the present invention consists in the novel lasting machine or wiping mechanism and the novel features of arrangement, design, combination and detail herein illustrated, described 10 or claimed.

The accompanying two sheets of drawings contain the following figures.

Figure 1 is what may be considered a front elevation of a lasting machine or a 15 wiping mechanism embodying the present invention, the wiper plates standing at the extreme right, and the shoe A being supposed to be held to the right thereof in inverted position and with the toe directed 20 leftward.

Fig. 2 is a top plan view of the machine.

Fig. 3 is a left elevation of certain adjusting parts in Figs. 1 and 2.

Fig. 4 is a central longitudinal section on 25 the plane 4—4 of Fig. 2.

Fig. 5 is a detailed plan view on an enlarged scale of the wiper plates and their immediately connected mechanism, with the wiper cover plate removed. The set of wiper 30 plates are shown in position for wiping a right shoe.

Fig. 6 is similar to Fig. 5, but with each wiper plate reversed, so as to readapt the wiping mechanism to a left shoe.

Fig. 7 is a top plan view of certain of the 35 underlying parts in Figs. 5 and 6, the majority of the movable parts being omitted.

Fig. 8 is a detached plan view of the gear segments employed for reversing the wiper 40 plates.

Fig. 9 is a detached plan view of the gear segments or carriers by which the plates are swung to move their wiping edges toward and from each other as the wiping device 45 is bodily advanced toward the shoe and retracted.

Above any suitable base may be mounted a longitudinally and vertically adjustable support or post 12, and above this is shown 50 a carriage 13, having a dovetailed engagement with the post to permit transverse adjustment of the wiping mechanism. Upstanding from the carriage 13 are opposite brackets 14. At the top of the brackets are 55 bearings 15 for trunnions 16, between which the entire wiping mechanism or "head" is supported, the trunnions permitting swinging adjustment to secure any desired longitudinal incline or tilt.

Before describing the details of the wiping head I will mention the usual or necessary motions, adjustments and operations involved in toe wiping. In addition to the longitudinal, vertical and transverse adjust- 60

ments already mentioned, and the longitudi-

nal tilting about the trunnions 16, I have shown means for effecting a lateral incline or tilt of the wiping head. A horizontal swinging adjustment about a convenient vertical axis to change the direction of wiping 70 action with respect to the shoe may sometimes be employed, but is not herein shown, as it is assumed that the shoe holding jack will be capable of a swinging movement to secure the desired relative adjustment. 75

Finally, we come to the operative wiping movements of the wiper plates. These movements of the wiper plates toward and from the shoe are supposed to take place in conjunction with the bodily lifting and lowering movements, before mentioned, and subsequently to effecting the various adjusting movements previously mentioned. The wiping movement herein is shown as consisting of the bodily advance and retraction of 80 the wiper plates in a longitudinal direction accompanied by a swinging or converging movement during the advance, the retreating movement of the plates being accompanied by their separation or swinging apart. 85

Where the contour of toes differs extensively the wiper plates must usually be interchanged for other plates of the proper contour. By the present invention, when the pair or set of plates for one shoe are replaced by another pair or set of the proper contour, the interchange is complete and no further interchange is necessary for the mate, since, according to this invention, the same set of plates is made to serve for wiping both the right and left shoes of a pair. 95

The movement or shifting or adjustment of the wiper plates hereof to adapt them from one to the other shoe consists herein, as before stated, substantially in a reversal 100 of the position of each plate without reversing its location from one side to the other of the machine; and preferably the reversal is made by a rotation in its own plane substantially about a vertical axis located 110 within the area of the plate. This invention comprises means for quickly and conveniently reversing the wiper plates in the manner described to prepare the machine for operation upon rights and lefts. 115

Generally speaking, the trunnions 16 at the top of the brackets support a cylindrical shell or housing 17, which is hung between them so as to swing about a transverse horizontal axis to permit adjustment of the longitudinal tilt. 120

Within the shell 17 is a cylindrical member, which may be termed a carrier 18. The member 18 is adapted to move in two modes within the shell. Firstly, it may slightly 125 rotate or oscillate to secure the desired lateral tilt of the wiping head. Secondly, it may move bodily longitudinally so as to carry the wiper plates toward and from the work during the wiping action. The car- 130

rier 18, therefore, is the actively movable member during the wiping operations. This carrier has a forward extension 19, which affords the support for the wiper plates 20 and 21, and the various fittings associated with them, which will be subsequently described.

The near wiper plate 20 and the far plate 21 are constructed on the same principles, but are not identical in shape or contour. As before stated, each of them is adapted to be shifted for the purpose of reversal, and for this purpose each plate is provided with a suitably located vertical pivot 22. As shown, each pivot 22 is an interior pivot or axis, being located substantially near to the middle portion of the area of each wiper plate. By this arrangement each plate, in rotating horizontally to reverse itself, does so without substantially changing its location in the machine. Equivalent rotary or other reversing movements might be employed to the same end.

I do not attempt to employ the same plate contour for both shoes of a pair, but, on the contrary, each wiper plate is provided at its periphery with two separate contour portions adapted respectively to right and left shoes. Thus, as shown in Fig. 5, the wiper plate 20 has a contour 23 for a portion of the toe of a right shoe, and the wiper plate 21 has a coöperating contour 24 for the opposite side of the toe of the right shoe. Fig. 5, therefore, shows the position of the plates for wiping a right shoe. When the plates are reversed by a rotation around the pivots 22, they assume the Fig. 6 position, in which it will be seen that the wiper plate 20 has a contour 25 adapted for one side of the toe of a left shoe, while the wiper plate 24 has a coöperating contour 26 for the left shoe.

Each of the two wiper plates is so shaped and fitted with regard to the wiping contours and the center of rotation that in either operative position the wiping may be effectively performed without conflict or obstructions by other portions of the plate. Owing to this advantageous arrangement, no readjustment whatsoever of the location of the plates is required, or other adjustment with respect to the wiping head, and the simple rotary reversing movement described brings about the complete change from the Fig. 5 to the Fig. 6 position to convert the mechanism from right to left shoes.

It will be noticed that the reversing action is one requiring very slight muscular effort, since practically only the two wiper plates of insignificant weight are required to be shifted, and, as will be seen, I have provided that the two plates with a single manual movement or adjustment may be simultaneously reversed in an extremely

convenient and expeditious manner. This mere plate reversing action completely converts the machine for wiping rights or lefts, with the exception of the requirement that the lateral tilt be reversed, and connections 70 may be provided herein such that the throw of a single lever or manipulating part may simultaneously reverse the wiper plates and also the lateral tilt, if desired.

When the wiper plates have been set in either of their operative positions, it is desirable to lock them in such adjustment, so that they may be held effectively and rigidly with relation to the mechanism for causing the wiping movements of the plates. For this purpose each wiper plate is provided with a pair of recesses or pin-holes 27 and 28. In Fig. 5 the locking recess 28 of plate 21, and the recess 27 of plate 20, are shown engaged by locking pins later to be described, and in Fig. 6 the other recesses are so engaged.

The actual plate reversing operation may be performed by any convenient connections. I have shown attached beneath each wiper plate a pinion 29, which is engaged by a longitudinally moving rack 30. For convenience, the racks 30, instead of being straight, are shaped and moved along an arc, each rack being formed or connected to an arc-shaped slide 31, and each of the two slides provided with an upstanding handle 32. The handles are located in close proximity so that they may be simultaneously grasped to operate both racks and reverses both plates in one motion. Fig. 5 shows the two handles thrown from the operator to set the wiper plates for a right shoe, and in Fig. 6 the two handles have been pulled toward the operator to reverse the plates. As seen in these figures, and in Fig. 8, the curved slides 31 are separate, so that, if desired, the plates could be independently moved, or relative adjustment might be effected, for example, by slipping a thin separator between the abutting ends of the slides.

The curved slides 31, which carry the reversing racks 30, are not fitted directly on the forward extension 19 of the carrier, but instead are slidably fitted by means of dovetails 33 on the slides 31, with curved slots formed at 34 in segmental carriers 40, to be later described.

These segmental or curved carriers 40 are also provided with outstanding ears 35, in which are fitted to slide vertically the spring locking pins 36, which engage the locking recesses 27, 28, of the wiper plates, already mentioned. See Fig. 1. The locking pins 36 are pressed yieldingly upwardly so as to normally engage in the locking recesses, but may be drawn downwardly to permit the reversal of the wiper plates by means of an unlocking device or lever 37, one end of

which is recessed to engage a groove in the lower end of each locking pin, and the two levers 37 at the two sides being both mounted on a common shaft 38, which may be 5 swung by lifting a convenient handle 39 to depress both locking pins. This permits the handle 32 to be manipulated for reversing the wiper plates. The handle normally rests on a supporting pin 39a.

10 I prefer that the converging or swinging movements of the wiper plates, which take place simultaneously with their advance when acting upon the shoe, shall be a swinging about point F, which is the tip or apex of 15 the contour of the toe, and is also the point at which the contours of the two wiper plates meet. By this mode of swinging the wiping contour around the tip of the toe is maintained continuous throughout the wiping movements and without the need of 20 overlapping the plates.

The members 40, therefore, which directly carry the wiper plates, are fitted to move about the point F as a center, and for this 25 purpose they are constructed of a curved or segmental shape. The vertical pivots 22, about which the wiper plates rotate for their reversing adjustment, are carried directly at the upper sides of the segmental 30 carriers 40, so that the latter, when moving circularly about the center F, will bodily carry the respective wiper plates toward and from each other with a swinging movement about the same center. As before 35 stated, each segmental carrier also supports the ear 35, in which is mounted the wiper plate locking pin, so that, when each plate is adjusted and locked, it is held by the pivot 22 and the locking pin 36 in rigid 40 relation with the carrier.

Each segmental carrier 40 is shown provided with a curved toothed rack 41, by which its movements about the center F may be effected.

45 In order to guide the segmental carriers in their swinging movements, an upstanding dovetailed guide 42 is mounted directly on the forward extension 19 of the actuating carrier 18. See Figs. 4 and 7. The under 50 sides of the segmental carriers are correspondingly undercut.

Displacement of the wiper plates vertically is prevented by their engagement with the pinions 29, racks 30 and portions of the 55 segmental carriers 40 beneath the plates, while above the wiper plates is securely fastened a cover plate 43, which also substantially incloses and protects the working mechanism. The cover plate 43 is bolted 60 down to the extension 19 by means of bolts 44, two of which serve also as axles for the pinions about to be described.

In order to effect the swinging movements of the segmental carriers 40 so as to 65 move the wiper plates together and apart,

the racks 41 in said carriers may be engaged, as shown in Figs. 5 and 6, by pinions 45, to which are rigidly secured pinions 46 engaging longitudinal racks 47 at the opposite sides of the head. The racks 47 are so arranged as not to partake of the longitudinal wiping movements of the head. Therefore, when the carrier 18 is thrust forwardly, advancing the wiper plates and segmental carriers and the pinions 45 and 46, the racks 75 remain stationary, causing the rotation of the pinions, the latter acting upon the curved racks 41 and the segmental carriers to cause the required swinging movements of the latter.

80 In order to secure the racks 47 to the shell 17, so as to permit relative rotation during the adjustment of lateral tilt, the two racks are shown bolted rigidly to a ring 48, surrounding a convenient portion of the 85 shell 17 and held against longitudinal movement by one or more angle pieces or straps 49.

By the described mechanisms the mere thrusting forwardly and retracting of the 90 longitudinal carrier 18 brings about the complete wiping movements of the wiper plates. A handle 50 may be employed to effect the movements, this being arranged within convenient access, so that the operative may 95 manipulate the handle with the left hand while the right hand takes care of the shoe, and one foot effects the elevation and the lowering of the wiping head by the usual pedal.

100 The wiping handle 50 is fulcrumed on a floating pivot 51 and is connected by a stem 52 with a head 53, having a swivel engagement with the hollow interior of the carrier 18. The swivel connection permits the carrier to be relatively rotated for adjusting lateral tilt of the head. Upon the handle 50 is shown the usual latch handle 54, which by means of a latch and the rack 55 is adapted to lock in forward position the 110 carrier 18 and the wiper plates.

105 The adjustment of lateral tilt may be effected by a hand wheel 56 secured on a threaded shaft 57, passing through threaded ears 58 upstanding from the shell 17. Secured on the shaft 57 between the ears are a pair of lugs 59 adapted to push forward or rearward a boss 60, which is recessed and loosely surrounds the shaft 57. Downwardly extending from the boss 60 are a 115 pair of arms 61, which partly reach around and have a splined or grasping engagement with longitudinal grooves 62 formed in the carrier 18. By throwing the boss 60 forward or rearward by means of the handle 120 56, the carrier 18 is caused to oscillate in either direction, so as to bodily tilt the entire wiping mechanism from a horizontal 125 position in either direction.

130 A convenient way to alter the longitudi-

- nal tilt is by the mechanism shown in Fig. 1, in which, between a lug 63 on the shell 17 and a lug 64 on the bracket 14, are extended a pair of oppositely threaded bolts 65 engaged by the oppositely threaded sides of the hub of the adjusting hand wheel 66. By turning the hand wheel in one direction or the other the rear end of the shell 17 is lifted or lowered, as desired.
- 10 The practical operation of the described machine may be simply that, with the shoe in proper relation to the wiping mechanism, the latter is manipulated in the usual manner and by the assistance of the handle 50. Assuming that the parts are in the Fig. 5 position, the wiping of the right shoe will thus be completed, at the end of which the operative will shift the wiping handle 50 leftward to retract the wiping mechanism.
- 20 Before commencing the wiping operation on the left shoe, the operative with one hand will slightly lift the unlocking handle 39 and then reverse each wiper plate by simultaneously pulling the handles 32 toward him; the locking pins 36 automatically entering the locking recesses in the wiper plates. The wiping handle 50 is then again manipulated for wiping the left shoe. The capability of quick reversal renders it practical and expedient to perform the lasting of shoes in this advantageous manner, the two shoes of a pair being lasted in immediate succession, giving superior uniformity in quality and workmanship.
- 30 It will thus be seen that I have described a lasting machine or wiping mechanism embodying the novel principles of the present invention and attaining the objects and advantages thereof; and further advantages in the described structure will be apparent to those skilled in the art. Many matters of mere design, arrangement, detail or sub-combination may be variously modified without departing from the underlying principles of the invention, and, therefore, there is no intention to limit the present invention to such features excepting in so far as the same are recited in the appended claims.
- 40 50 What is claimed is:
1. In a shoe wiping machine, a movable wiper plate carrier, and a wiper plate having different wiping contours and shiftable on said carrier without removal therefrom to bring the desired wiping contour into operative position.
  2. In a shoe wiping machine, a movable wiper plate carrier, a wiper plate having different wiping contours and shiftable on said carrier without removal therefrom to bring the desired wiping contour into operative position, and means to lock the plate rigidly on the carrier in either operative position.
  3. In a shoe wiping machine, a movable wiper plate carrier, a wiper plate having different wiping contours and shiftable on said carrier without removal therefrom to bring the desired wiping contour into operative position, means to lock the plate rigidly on the carrier in either operative position, and means to move the carrier to give wiping movements to the plate.
  4. In a shoe wiping machine, a movable wiper plate carrier, co-operative opposite wiper plates, each of said opposite wiper plates having different wiping contours shaped for right or left shoes, respectively, and both said plates being shiftable on said carrier without removal therefrom to bring the desired wiping contours into operative position, and means for co-operatively actuating said wiper plates during wiping.
  5. In a shoe wiping machine, a movable wiper plate carrier, and a wiper plate having different wiping contours and shiftable about an interior axis on said carrier without removal therefrom to bring the desired wiping contour into operative position.
  6. In a shoe wiping machine, a movable wiper plate carrier, and a wiper plate having different wiping contours and shiftable in its own plane on said carrier without removal therefrom to bring the desired wiping contour into operative position.
  7. In a shoe wiping machine, a wiper plate having two wiping contours, for rights and lefts, respectively.
  8. In a shoe wiping machine, a wiper plate having two wiping contours, for rights and lefts, respectively, and shiftable to bring either contour to wiping position.
  9. In a shoe wiping machine, a wiper plate having two wiping contours, for rights and lefts, respectively, and shiftable to bring either contour to wiping position by a movement substantially in its own plane.
  10. In a shoe wiping machine, plate carrying means, a plurality of wiper plates carried thereby, each wiper plate having a plurality of different contours, and means for shifting each wiper plate to bring the desired wiping contour into operative position without removal from or inversion of the carrier.
  11. In a shoe wiping machine, plate carrying means, a pair of opposite wiper plates carried thereby, each wiper plate having a plurality of different contours, and means for shifting both wiper plates to bring the desired wiping contours into operative position without removal from or inversion of the carrier.
  12. In a shoe wiping machine, separate wiper plates for opposite sides of the shoe contour, and means to shift each plate while maintaining it at the same side of the contour, in such manner as to change over the machine for rights and lefts.
  13. In a shoe wiping machine, separate

6

5 wiper plates for opposite sides of the shoe contour, each plate having two wiping contours, for rights and lefts, respectively, and means to shift each plate to bring a different wiping contour into operative position while maintaining it at the same side of the shoe contour, in such manner as to change over the machine for rights and lefts.

10 14. In a shoe wiping machine, separate wiper plates for opposite sides of the shoe contour, and means to shift each plate by rotation in its own plane, said plates being so constructed that such shifting serves to change over the machine for rights and lefts.

15 15. In a shoe wiping machine, the combination of separate wiper plates for opposite sides of the shoe contour to be wiped, a movable carrier for each of said plates, connections permitting shifting of each plate 20 on its carrier for rights and lefts, and means for simultaneously actuating the carriers to produce wiping movements of the plates.

25 16. In a shoe wiping machine, the combination of separate wiper plates for opposite sides of the shoe contour to be wiped, each having two contours for rights and lefts, respectively, a movable carrier for each of said plates, connections permitting shifting of each plate on its carrier, and means for 30 simultaneously actuating the carriers to produce wiping movements of the plates.

35 17. In a shoe wiping machine, the combination of separate wiper plates for opposite sides of the shoe contour to be wiped, each having two contours for rights and lefts, respectively, a movable carrier for each of said plates, connections permitting shifting of each plate on its carrier, by rotation in its own plane, and means for simu-

5 taneously actuating the carriers to produce 40 wiping movements of the plates.

18. In a shoe wiping machine, the combination of separate wiper plates for opposite sides of the shoe contour to be wiped, each having two contours for rights and lefts, 45 respectively, a movable carrier for each of said plates, connections permitting shifting of each plate on its carrier, means for locking each plate to its carrier in either position, and means for simultaneously actuating the carriers to produce wiping movements of the plates.

19. In a shoe wiping machine, the combination of separate wiper plates for opposite sides of the shoe contour to be wiped, a 55 movable carrier for each of said plates, connections permitting shifting of each plate on its carrier for rights and lefts, a device for simultaneously shifting both plates, and means for simultaneously actuating the carriers to produce wiping movements of the plates.

20. In a shoe wiping machine, the combination of separate wiper plates for opposite sides of the shoe contour to be wiped, each 65 having two contours for rights and lefts, respectively, a movable carrier for each of said plates, connections permitting shifting of each plate on its carrier, a device for simultaneously shifting both plates, means 70 for locking each plate to its carrier in either position, and means for simultaneously actuating the carriers to produce wiping movements of the plates.

In testimony whereof, I have affixed my 75
signature hereto.

ANGELO PERRI.
